UNITED STATES PATENT OFFICE.

MICHELE CIGANENKO, OF PITTSBURGH, PENNSYLVANIA.

TORPEDO-REPELLING DEVICE.

1,273,330.

Specification of Letters Patent.

Patented July 23, 1918.

Application filed July 27, 1917. Serial No. 183,051.

To all whom it may concern:

Be it known that I, MICHELE CIGANENKO, a subject of the Czar of Russia, resident of S. S. Pittsburgh, county of Allegheny, and 5 State of Pennsylvania, have invented certain new and useful Improvements in Torpedo-Repelling Devices, of which the following is a specification.

This invention relates to improvements in 10 torpedo repelling devices, as attached to the hulls of vessels when within a danger zone.

The principal object of the invention is to provide devices extending longitudinally of the vessel's side and at a considerable 15 distance therefrom, or which may be folded compactly against the hull.

A further object is to provide means at the rear or stern of the vessel which may be completely raised out of the water when not 20 in use, thereby avoiding impediment during navigation.

These and other like objects are attained by the novel construction and combination of parts hereafter described and shown in 25 the accompanying drawings, forming a material part of this disclosure, and in which—

Figure 1 is a side elevational view of a conventional type of vessel and indicating the application of the invention.

30 Fig. 2 is a top plan view of the same.

Fig. 3 is an enlarged fragmental top plan view indicating the means by which the guard elements are attached to the vessel.

Fig. 4 is a vertical sectional view taken 35 on line 4—4 of Fig. 3.

Fig. 5 is a sectional view drawn to an enlarged scale, showing one of the buoyant elements employed at the stern of the boat.

Fig. 6 is a fragmental top plan view indicating their arrangement.

Fig. 7 is a vertical sectional view taken on line 7—7 of Fig. 6.

Fig. 8 is a perspective view showing a fragment of the wire or cable inclosed in a 45 cork, covering of rectangular cross-section.

Fig. 9 is a similar perspective view showing one of the support rods, upon which is wound the cork covered wire indicated in Fig. 8.

50 Fig. 10 is a sectional view showing a single row of the support elements.

Fig. 11 is a sectional view showing a double row of the same.

Fig. 12 is a similar sectional view showing 55 a plurality of rows, interengaged and connected together, and

Fig. 13 shows a modification of the baffle plate elements, together with their supports.

In the drawings, the numeral 10 represents the hull of the boat, the same being 60 provided with the usual decks, smokestacks, masts, etc.

Along each side of the vessel, at a point above the normal water line, are engaged brackets 14, the same having outstanding 65 flanged elements 15, and containing elongated slots 16, in which the shank of the bolts 17 may freely operate. Pivoted secured by these bolts are links 18, while rearward of the brackets 14, are other brackets 20, having extending flanges 21, co-incident with which are similar flanges 22, formed with a strip element 23, the flanged portion containing a pin 25, by means of which links 26 are pivotally engaged, similar links 70 28 being secured by pins 29, affixed in the flanges 30 and 31, the former being formed integrally with the strip 23, while the latter has an extending foot 32, secured to the lower part of the vessel hull, as can best be 80 seen in Fig. 4, the pins being arranged one directly over another so as to be in the same axial plane.

Plates 35 extending the full length of the vessel, have attached upon their inner surfaces at regular intervals strips 36, the ends being turned inwardly forming flanges 37 and 38, respectively, at the top and bottom, co-incident with which are the flanges 39 and 40, formed with the brackets 41 and 42, 90 also secured to the plates 35, the upper set of brackets containing pins 44, by means of which the links 18 and 26 are pivotally engaged, a similar pin 46 passing through the flanges 38 and 40 connecting the lower link 95 28, both sets of pins being in the same axial plane.

At the extreme front of the vessel are secured brackets 50, in which are hingedly engaged within slots formed therein, links 100 51 pivoted by pins 52, similar brackets being secured to the plate 35 and which are normally held parallel with the center line of the vessel by links 53 pivoted at their opposite end upon the brackets 54 secured 105 to the hull of the vessel in the manner before described.

When it is desired to move the plate 35 outwardly the links 26 and 53 are turned upon their pivots, while the longer links 18 110 and 51 are not only turned upon their pivots but allowed to move forwardly within the

slots formed in their respective brackets, the plates being held rigidly outward, or by allowing the links to fold against the side of the vessel, pivoting in their brackets, the plate 35 may be brought closely adjacent to the hull.

Arranged at the rear or stern of the vessel are pairs of brackets 60 and 61, carrying pins 62 upon which are pivoted levers 63, the same being engaged with bearings 64 formed between flanges 65, of connecting bars 66, secured by flanges 67, to the buoyant elements 70 comprised of cork or other like material, contained in nets 72, the same having compartments 73, therein so as to hold the buoyant material in place even should the net become damaged.

A plurality of buoys 70 are used, the same being connected near their front ends by connections 68 having flanges 69 in their ends and with which are engaged the succeeding buoys.

A plurality of gratings 74 are extended between the buoys, which terminate at their lower end in relatively heavy elements 75, so that the entire structure is held in a relatively vertical pendant position.

Engaged with the hooks 80, set in the levers 63, are cables 81, passing over pulleys 82, to a winch or the like carried by the vessel and by means of which the buoyant structure at the rear of the vessel may be raised completely out of the water, as can be seen by the broken lines in Fig. 1, thereby offering no impediment to the free movement of the vessel, and it will be understood that the plates 35 are of a relatively thin cross-section and because of their position, being parallel with the center line of the vessel at all times, that the plates will present substantially no opposition to the movement through the water, and particularly so when they are folded closely adjacent to the vessel sides.

In the views, Figs. 9 to 13 inclusive, is indicated a preferred form of construction for the baffle plates, the same consisting of a wire 100, embedded in blocks of cork 101, the blocks being made of rectangular cross-section and so molded that the embedded wire may be coiled about a relatively rigid bar 102, a plurality of the coils being arranged in rows as shown in Figs. 10 to 13, inclusive, the several rows being held by

bands 106 so as to form a light strong and 55 buoyant structure of great elasticity and resilience.

In Fig. 13 single rows of the cork encircled elements 102 engaged by the bands 106, are connected together at uniform intervals 60 by interengaged transverse rods 110, the rods and bands being soldered or otherwise rigidly connected together at their points of intersection.

Having thus described my invention, what 65 I claim as new, and desire to secure by Letters Patent, is—

1. In a device as described, in combination, with the side of a ship, a plate extending along one side thereof, a strip secured 70 upon the inner face of said plate and formed at its opposite ends with right angular portions, angle strips also secured above and below the first strip to said plate and providing arms disposed parallel to the right 75 angular portions, similar strips secured upon the side of said ship and also providing the right angular portions and the arms, a bracket secured to the upper side of said ship so as to provide an additional arm, a 80 lever pivoted between the arms and right angular portions at the lower ends of said ship and plate, and another lever similarly pivoted at the upper end of said ship side and said plate, a pin projecting through the 85 upper arm of said plate, and a third lever slidably pivoted to the uppermost arm of the ship side and carrying at its outer end a depending sleeve engaging said pin.

2. In a device as described, in combination, with the stern of a ship, a pair of lever arms pivotally mounted thereon in projecting relation, a parallel series of cork buoyant elements, wire-mesh nets containing said buoyant elements, said nets having compartments for said elements, a pair of bearings 95 for said lever arms, each bearing consisting of a pin formed at opposite ends with parallel sides secured between and against the sides of said nets, and between said buoyant 100 elements, and a plurality of gratings extending between said buoyant elements and terminating at their lower ends in relatively heavy bodies.

In testimony whereof I have affixed my 105 signature.

MICHELE CIGANENKO.

Copies of this patent may be obtained for five cents each, by addressing the "Commissioner of Patents, Washington, D. C."
